UNITED STATES PATENT OFFICE.

JULIUS B. FENSTERWALD, OF BALTIMORE, MARYLAND, AND JACOB GEIGER, OF NASHVILLE, TENNESSEE, ASSIGNORS OF ONE-THIRD TO JOE FENSTERWALD, OF NASHVILLE, TENNESSEE.

BELT-RETAINING DEVICE.

1,069,774.

Specification of Letters Patent.

Patented Aug. 12, 1913.

Application filed February 1, 1912. Serial No. 674,683.

To all whom it may concern:

Be it known that we, JULIUS B. FENSTERWALD and JACOB GEIGER, citizens of the United States, residing, respectively, at 5 Baltimore, Maryland, and Nashville, in the county of Davidson, State of Tennessee, have invented a new and useful Belt-Retaining Device, of which the following is a specification.

10 The device forming the subject-matter of this application aims to provide a novel form of supporting member, adapted to be connected with the tongue of a buckle, and with a garment, whereby the buckle of which 15 the tongue constitutes a part, together with the belt which is engaged by the buckle, may be upheld upon the garment.

With the foregoing and other objects in view, which will appear as the description 20 proceeds, the invention resides in the combination and arrangement of parts and in the details of construction hereinafter described and claimed, it being understood that changes in the precise embodiment of invention herein disclosed can be made within 25 the scope of what is claimed without departing from the spirit of the invention.

In the drawings,—Figure 1 shows in perspective, a portion of a garment to which 30 one form of the invention has been applied; Fig. 2 is a perspective of a portion of a garment to which another form of the invention has been applied; Fig. 3 is a detail perspective of that form of supporting member which is employed in Fig. 1; and Fig. 4 is a detail perspective showing a modified form of the invention.

In the drawings, the numeral 1 indicates 35 a garment, which may be a pair of pantaloons. The garment 1 is split, as shown at 2, to form flaps 3 and 4. Upon the flap 3 there is commonly located a hook 5, adapted to engage with the loop 6 upon the flap 4. Instead of the hook 5, a button 7 is some- 40 times employed, as shown in Fig. 2, the button 7 being received in a buttonhole upon

the flap 4, as is common and well understood.

The belt which is applied to the garment is denoted by the numeral 8, and the ends 50 of the belt are united by a common buckle 9, having a tongue 10, engaging the holes 10' in one end of the belt.

The supporting member employed in Fig. 1, is shown in detail in Fig. 3, and is there 55 denoted generally by the numeral 11. This supporting member 11 is an open loop, bent as shown at 12, to form angularly disposed parts 14 and 15. The end 16 of the part 14 is bent upon itself, or is otherwise disposed, 60 to fashion an eye 17.

In practical operation, the tongue 10 of the buckle is inserted through the eye 17, the part 14 of the supporting member extending across the edge of the garment, and 65 the part 15 lying approximately parallel to the inner face of the garment, the end 18 of the part 15 being engaged over the hook 5, as will be readily understood upon an inspection of Fig. 1. 70

That form of the invention shown in Fig. 2 embraces many of the parts shown in Fig. 3, the parts already described in connection with Fig. 3 being indicated in Fig. 2 by the same reference numerals, with the suffix "a." 75 The end 18^a of the part 15^a, however, is prolonged to form a button-engaging loop 19, the loop 19 being contracted to form an entering throat 20. As will be readily understood, the stitching of the button 7 will 80 pass through the throat 20 and enter the loop 19.

If desired, the invention may be modified as shown in Fig. 4. The device there shown differs from the structure shown in Fig. 3, 85 only in the omission of the tongue receiving eye 17 of Fig. 3. Referring to Fig. 4, an open loop is shown, the same being bent as shown at 21, to form angularly disposed parts 22 and 23. The end bar 24 of the part 90 22 may be engaged with the tongue 10, and the end bar 25 of the part 23 may be engaged

with the hook 5, or with the button 7; the device, however, being adapted primarily for use in connection with the hook 5.

Having thus described the invention, what 5 is claimed is:—

A device of the class described comprising a loop flexed intermediate its ends to form angularly disposed parts, one of which parts is terminally provided with a tongue-receiving eye, the other of which parts is provided 10 with a projecting button-receiving throat opening into the loop.

In testimony that we claim the foregoing as our own, we have hereto affixed our signatures in the presence of two witnesses.

JULIUS B. FENSTERWALD.
JACOB GEIGER.

Witnesses (as to Fensterwald) :

I. B. MOSES,
FRANK A. SCHNEIDER.

Witnesses (as to Geiger) :

JNO. HARTNETT,
T. H. WOMACK.
